CAMERA-PROJECTOR HEAD FOR A PHOTORE- PRODUCTION UNIT OR SIMILAR ARTICLE

Joseph H. Wally, Jr., Shawnee Mission, Kans., assignor to
Western Blue Print Company, Kansas City, Mo., a cor-
poration of Missouri

Filed Dec. 16, 1968, Ser. No. 15,099

Term of patent 14 years

Int. Cl. D21—05

U.S. Cl. D61—1

FIG. 1

FIG. 2

FIG. 3

FIG. 1 is a perspective view of the side and one end of a camera-projector head for a photoreproduction unit or similar article showing my new design;

FIG. 2 is a side elevational view of the other side of the camera-projector head for a photoreproduction unit or similar article; and

FIG. 3 is an end view thereof opposite to that shown in FIG. 1, being taken along line 3—3 looking in the direction indicated by the arrows.

I claim:

The ornamental design for camera-projector head for a photoreproduction unit or similar article, substantially as shown and described.
